US0D1032972S

(12) **United States Design Patent** (10) **Patent No.:** **US D1,032,972 S**
(45) **Date of Patent:** **** Jun. 25, 2024**

(54) **PET STAIR**

(71) Applicant: **Ningbo Tianrun Digital Technology Group Co., Ltd.**, Ningbo (CN)

(72) Inventor: **Yang Cai**, Xinghua (CN)

(73) Assignee: **Ningbo Tianrun Digital Technology Group Co., Ltd.**, Ningbo (CN)

(**) Term: **15 Years**

(21) Appl. No.: **29/936,216**

(22) Filed: **Apr. 8, 2024**

(51) LOC (14) Cl. **30-03**

(52) U.S. Cl.

USPC **D30/199**

Primary Examiner — Susan Moon Lee

(57) **CLAIM**

The ornamental design for a pet stair, as shown and described.

DESCRIPTION

FIG. 1 is a front perspective view of a pet stair, showing my new design, in a first configuration;

FIG. 2 is a rear perspective view thereof;

FIG. 3 is a front perspective view of the pet stair, shown in a second configuration;

FIG. 4 is a rear perspective view thereof;

FIG. 5 is a top perspective view of a first component of the pet stair, shown separately for clarity;

FIG. 6 is a bottom perspective view thereof;

FIG. 7 is a front elevation view thereof;

FIG. 8 is a rear elevation view thereof;

FIG. 9 is a left side elevation view thereof;

FIG. 10 is a right side elevation view thereof;

FIG. 11 is a top plan view thereof;

FIG. 12 is a bottom view thereof;

FIG. 13 is a top perspective view of a second component of the pet stair, shown separately for clarity;

FIG. 14 is a bottom perspective view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof;

FIG. 20 is a bottom view thereof;

FIG. 21 is a top perspective view of a third component of the pet stair, shown separately for clarity;

FIG. 22 is a bottom perspective view thereof;

FIG. 23 is a front elevation view thereof;

FIG. 24 is a rear elevation view thereof;

FIG. 25 is a left side elevation view thereof;

FIG. 26 is a right side elevation view thereof;

FIG. 27 is a top plan view thereof;

FIG. 28 is a bottom view thereof;

FIG. 29 is a top perspective view of a fourth component of the pet stair, shown separately for clarity;

FIG. 30 is a bottom perspective view thereof;

FIG. 31 is a front elevation view thereof;

FIG. 32 is a rear elevation view thereof;

FIG. 33 is a left side elevation view thereof;

FIG. 34 is a right side elevation view thereof;

FIG. 35 is a top plan view thereof; and,

FIG. 36 is a bottom view thereof.
